CONTAINER

James E. Annen, Kalamazoo, Mich., assignor to
 Sutherland Paper Company, Kalamazoo,
 Mich.

Application March 7, 1938, Serial No. 194,263

6 Claims. (Cl. 229—51)

This invention relates to improvements in containers.

The main objects of this invention are:

First, to provide an improved quick opening 5 container having an end closure which may be quickly released and when released constitutes an effective replaceable cover.

Second, to provide a container of this type having fibrous side walls.

10 Third, to provide a container having fibrous side walls with means for effective attachment of a metal closure.

Fourth, to provide a structure having these advantages which is economical in its parts and 15 at the same time is suitable as a substantially sealed container for various food products and the like.

Objects pertaining to details and economies of my invention will definitely appear from the 20 description to follow. The invention is defined in the claims.

A device embodying the features of my invention is clearly illustrated in the accompanying drawing in which:

25 Fig. 1 is a perspective view of a closed container embodying the features of my invention.

Fig. 2 is a side elevation of the container and the end closure thereof prior to the attachment of the end closure.

30 Fig. 3 is an enlarged fragmentary view partially in longitudinal section with the closure in position.

Fig. 4 is a fragmentary longitudinal section prior to the attachment of the end closure.

Fig. 5 is a fragmentary view of the rim element prior to its attachment to the wall of the container.

Fig. 6 is a fragmentary side elevation illustrating the step of freeing the closure.

Fig. 7 is a fragmentary longitudinal section showing a closure in position as a covering after the tearing strip has been completely removed.

In the embodiment of my invention illustrated the side wall 1 of the container is formed of fibrous material and is provided with an outer facing layer 2 which in practice may be the ornamental label. The cover 3 is of metal and is of the depressed type having an upwardly projecting side rim portion 4 terminating in an 50 out-turned flange 5. I provide the wall 1 with a rim strip designated generally by the numeral 6. This is preferably formed of a strip of metal of suitable length to entirely embrace or encircle the container side wall and has a plurality of fastening elements 7 struck in therefrom and

adapted to be embedded in the fibrous wall of the container as clearly shown in Figs. 3 and 4. At its upper edge this rim is provided with an out-turned flange 8 over which the closure flange 5 is seamed as at 9, see Fig. 3.

5 The rim is provided with a weakened tearing zone 10 between the fastener element 7 and its flange 8, preferably substantially spaced from the flange, thus providing a tearing strip 11. The fastener elements are carried by this tearing strip. The tearing strip terminates in a tongue 12 with which the key 13 may be engaged so that by engaging the key which is slotted at 14 to receive the tongue, the tearing strip is rolled up on 15 the key, the fastening elements being withdrawn from the wall of the container without materially or objectionably tearing the wall.

After the tearing strip has been removed the portion of the rim above the tearing zone 10 constitutes a flange designated 15 in Fig. 7 telescoping with the outside of the container wall so that a very effective replaceable cover results after the closure is freed. This renders the container especially desirable for many food products which are ordinarily used over a period of time 25 instead of the entire contents of the container being used immediately after opening.

The container may be easily sealed, that is, the closure is easily attached by machinery now known or by such machinery slightly modified. 30 When closed the container is very secure and at the same time may be quickly freed. When freed an attractive container is provided which may be repeatedly opened and closed. The container in its originally sealed condition is attractive in that the openings 16 resulting from punching out the fastener elements 7 expose the label, which ordinarily is colored, and thereby the container presents a novel appearance.

35 I have illustrated and described my invention in an embodiment which I have found very practical. I have not attempted to illustrate or describe certain modifications or adaptations which might be necessary for containers of different shapes as it is believed this disclosure will enable 45 those skilled in the art to embody or adapt my invention as may be desired.

Having thus described my invention what I 40 claim as new and desire to secure by Letters Patent is:

50 1. A container having a side wall of fibrous material, a rim strip of metal wrapped around said container side wall and having a plurality of integral wall penetrating fastening elements 55 in withdrawable engagement with the wall of the

container, said rim strip being provided with an out-turned flange at its upper end and having a weakened tearing zone at the outer side of its fastening elements substantially spaced from 5 said flange, the portion of said strip below said zone constituting a tearing strip, and a closure telescoping within the container side wall and having an out-turned flange at its upper end seamed over the out-turned flange of said rim 10 strip whereby the closure may be freed by stripping the tearing strip portion of the rim strip from the container side wall, the portion of said rim strip above the tearing zone constituting a depending closure flange after the closure has 15 been freed by the removal of the tearing strip.

2. A container having a side wall of fibrous material, a rim strip of metal wrapped around said container side wall and having a plurality of integral wall penetrating fastening elements in 20 withdrawable engagement with the wall of the container, said rim strip being provided with an out-turned flange at its upper end and having a weakened tearing zone at the outer side of its fastening elements substantially spaced from said 25 flange, the portion of said strip below said zone constituting a tearing strip, and a closure seamed over the out-turned flange of said rim strip whereby the closure may be freed by stripping the tearing strip portion of the rim strip from 30 the container side wall.

3. A container having a side wall of fibrous material, a rim strip of metal wrapped around said container side wall and having a plurality of integral wall penetrating fastening elements in 35 withdrawable engagement with the wall of the container, said rim strip being provided with an out-turned flange at its upper end and having a weakened tearing zone at the outer side of its fastening elements substantially spaced from said

flange, the portion of said strip below said zone constituting a tearing strip.

4. A container having a side wall of fibrous material, a rim of metal embracing said container side wall and provided with fastening means in 5 detachable engagement with the wall of the container, said rim having a weakened tearing zone at the outer side of its fastening members, the portion of said rim below said tearing zone constituting a tearing strip, and a closure telescoping 10 within the container side wall and secured to said rim whereby the closure may be freed by stripping the tearing strip portion of the rim from the container side wall, the portion of said rim above the tearing zone constituting a depending closure flange after the tearing strip has 15 been removed for freeing the closure.

5. A container having a side wall of fibrous material, a rim of metal embracing said container side wall and provided with fastening means in 20 detachable engagement with the wall of the container, said rim having a weakened tearing zone at the outer side of its fastening members, the portion of said rim below said tearing zone constituting a tearing strip, and a closure secured to said rim whereby the closure may be freed by stripping the tearing strip portion of the rim from the container side wall.

6. A container having a side wall, and a rim embracing said container side wall and provided with a plurality of wall penetrating fastening elements in detachable engagement with the wall of the container, said rim having a tearing zone at the outer side of its said securing means, the portion of said rim below said tearing zone provided with said fastening elements constituting a tearing strip.
